UNITED STATES PATENT OFFICE.

FREDRICK HERMAN, OF REDFIELD, DAKOTA TERRITORY.

TRACK-LAYING APPARATUS.

SPECIFICATION forming part of Letters Patent No. 395,053, dated December 25, 1888.

Application filed July 5, 1888. Serial No. 279,054. (No model.)

To all whom it may concern:

Be it known that I, FREDRICK HERMAN, of Redfield, in the county of Spink and Territory of Dakota, have invented a new and Improved Track - Laying Apparatus, of which the following is a full, clear, and exact description.

My invention relates to an apparatus for laying rails on ties or other substructure of a road-bed to form a railway-track; and the invention has for its object to provide a simple, efficient, and durable apparatus of this character which may be operated to lay the rails of straight or curved tracks to perfect gage and with economy of time and labor.

The invention consists in certain novel features of construction and combinations of parts of the track-laying apparatus, all as hereinafter described and claimed.

Reference is to be had to the accompanying drawings, forming a part of this specification, in which similar letters of reference indicate corresponding parts in all the figures.

Figure 1 is a plan view of my improved track-laying apparatus on the track. Fig. 2 is a cross-section thereof, taken on the line 1 1 in Fig. 1. Fig. 3 is a central longitudinal vertical section of the apparatus, taken on the line 2 2 in Fig. 1. Fig. 4 is a detail plan view taken on the line 3 3 in Fig. 10, and illustrates the outer rail-supports and their tripping devices. Fig. 5 is a side elevation of the track-laying apparatus. Fig. 6 is a detail plan view illustrating the track-placer-latch devices.

Fig. 7 is a perspective view of one of the tripping-levers of the placer-head. Fig. 8 is a vertical transverse section taken on the line 4 4 in Fig. 1. Fig. 9 is a cross-section taken on the line 5 5 in Fig. 1, and Fig. 10 is a transverse section taken on the line 6 6 in Fig. 1.

The track-laying apparatus consists of two structures, a rail-carrying car, A, and a rail-placer, B, connected as presently described. The car is made with opposite side stringer-beams, a^a , and cross-timbers a' , securely bolted together and supported by two two-wheeled trucks held in suitable bearings or boxes on the car-frame. The car-wheels a^2 are provided with double flanges which lap over both sides of the heads of the rails C dropped from the placer, and hold them in perfect gage until they are spiked or otherwise secured to

the ties or road-bed, and as hereinafter more fully explained. Suitable truss-braces, a^3 , strengthen the car-frame.

On the frame there is journaled a transverse shaft, d , to which are fixed eccentrically a pair of brake-shoes, D D, which may be pressed against the laid rails C C by means of a lever, d' , which is fixed to the shaft d , and may be locked into any one of the teeth of a ratchet-bar, d^2 , secured to the car-frame. This brake device enables one man to stop the car at proper place and holds the car at rest until one pair of track-rails is run from it onto the placer B and let down therefrom to the road-bed, and should the forward car-wheels run a little past the ends of the last-laid pair of rails the brake-shoes D D will still hold the car platform or frame up level at proper position to discharge the next pair of rails from it onto the placer B. A spring, d^3 , held to the lever d' and hooking at its rear end under the car-frame, normally lifts the free end of the lever and holds the brake device out of action.

Across the front of the car-frame is bolted a metal bar, a^4 , from which the main longitudinal frame-beams $b b$ of the rail-placer B are hung by U bolts or clevises $b' b'$. The forward ends of these beams $b b$ are connected by a heavy cross bar or timber, b^2 , from which the principal parts of the rail-placer are supported, as presently explained, and the rear ends of the beams $b b$ are connected by a metal plate, b^3 , which may be re-enforced by a thinner metal plate, b^4 , placed on top of it. The back end of the placer rests between upper and lower cross-bars E E, which are bolted to the car-frame and are provided with a series of holes, e , through any two of which two pins, F F, may be passed. These pins pass freely through holes in the placer-plate b^3 or the plates $b^3 b^4$, and form guides on which the back end of the placer may move up or down, the pins having heads which prevent them falling through the upper cross-bar E of the car-frame. The pins F F in connection with the series of holes e also provide for laying the rails from the placer on either right or left hand curves of the railroad-track, as hereinafter described.

A vertical bar or pin, G, which is fixed at the lateral centers of the cross-bars E E,

- passes through a transverse slot, g , made in the placer-plate b^1 or the plates $b^3 b^4$, so as not to prevent the lateral movement of the back end of the placer, and said bar G is provided 5 with upper and lower notches, $g' g^2$, into either one of which a spring-pressed latch-bar, H , pivoted to the placer-plate b^1 , is adapted to enter, whereby the forward end of the placer may be held down onto the track-ties or be held up clear of the ties during the 10 placing of the rails. A keeper, h^2 , is provided for the free end of the latch-bar. A couple of springs, $I I$, which are held at their centers to the placer-beams $b b$, act by their free ends beneath the upper cross-bar E and one of the car-frame bars a' , to force down the back 15 end of the placer and raise its forward end from the road-bed when allowed to do so by the latch.
- 20 To the latch H is connected a rod, h , which extends forward to an arm, j , which is fixed to a shaft, J , journaled transversely on the placer-beams $b b$ forward of the fulcrum-clevises thereof. This shaft J may be turned to 25 release the latch H from its detent-bar G by turning a lever, J' , adjusted to one end of the shaft, or by pressing down onto either one of two arms, $J^2 J^3$, which are fixed to and project forward from the shaft. A spring, H' , which 30 is fixed to the placer-frame or to a bolt and nut holding or carrying trough, b^5 , on said frame, normally presses upward on the shaft-arms J^2 to assure the free engagement of the latch H with the bar G . The placer-frame also 35 has a metal plate or floor, b^6 , in front of the trough b^5 to accommodate short pieces of rails or fish-plates, or chair-plates, or other fittings of the track being laid by the machine, and the car A is also provided with a table or 40 trough, a^5 , for similar purpose. The placer-beams $b b$ are also provided with depending metal brackets or irons $b^7 b^8$, on and across which pieces of rails or other fittings may be carried.
- 45 On one of the car-frame cross-bars a' , preferably the second one from the front, is held at its center by pins k' an elastic rod, K , the opposite inclined parts of which rise gradually to points where the rod is bent downward 50 to form shoulders $k k$, which normally project above the tops of the cross-bar a' and form fulcrum-points against which the rails C , when slid to the sides of the car, may be set to adjust the rails in proper relation to the 55 front end rollers a^6 , journaled on the car to allow the rails to be run out forward over said rollers onto the rail-supports of the placer B , from which the rails will be dropped to the ties or road-bed, as presently described. The 60 rails C will preferably be loaded from platforms at the side of the track onto the center of the car, and as one pair of rails is drawn outward to the sides of the car they will depress the shoulders $k k$ of the rod K until the 65 rails pass the shoulders, which then spring upward to form the rail-adjusting fulcrums above mentioned. The extremities of the rod

K are bent to form handles k^2 , by pressing which the shoulders of the rod may be held below the car cross-bar a' by hand while the 70 rails are being shifted over to the center of the car when loading it. The car is also provided with a pair of rear rollers, $a^6 a^6$, over which rails may be run in loading the car from the rear end or on which long rails will 75 have support as they are run forward to the placer.

The forward end or head of the rail-placer B includes important features of my invention and will be next described, as follows: A 80 transverse head-plate, L , is held to the placer-head beam b^2 by a bolt, l , which passes through the plate, and an arched brace, l' , interposed between the plate and head-beam. Two gage-plates, $M M$, which hang vertically at each 85 side of the placer-head, are provided with in-bent ends or head-pieces $m m$, which lap onto the head-plate L , and are held thereto by bolt ends $n' n'$, which are formed at the upper ends of the two front and rear parts or limbs 90 of the placer-legs $N N$, the foot-plates n of which are adapted to support the placer-head on the ties c of the road-bed on which the rails C are to be laid. The gage-plates M and legs N are separated in pairs at each side of the 95 placer to form two vertical spaces, $O O$, to accommodate one pair of rails $C C$ and hold them to proper gage as they fall to the road-bed, as hereinafter more fully explained. The bolt l also holds to the under side of the cross-beam b^2 the upper center part of an arched brace-bar, n^2 , the lower ends of which are fixed to the opposite rail-gage legs $N N$ of the placer to stay them laterally. The gage-plates $M M$ do not extend downward as far as 100 the legs N , as the plates are required only for holding the rails laterally and not to support the placer from the ties of the track.

The front and rear parts of each of the placer-legs N converge from the opposite ends 110 of its foot-plate n to the beam b^2 , to which they are held by a bolt, p , which also gives a bearing to the lower end of the shaft of a vertically-ranging conical roller, P , the upper bearing of which is in an eyebolt, p' , held to the 115 leg. The bolt p also serves as a journal-bearing for the adjacent rail-supporting and trip-roller S , presently described. The roller P operates with another opposing roller, R , in guiding the rail C from the car A onto the 120 trip-roller S of the placer. This roller R is journaled on a pin or shaft, t , which is stepped in a lug, m' , formed on or fixed to the adjacent gage-plate M , and is formed as the lower 125 end of a metal bar, T , which is bent twice, or laterally and downward, so that it may be held to the head-plate L by the bolt ends n' of the placer-legs N , and these bolt ends also hold to the head-plate, and preferably between the bar T and the in-bent head-piece m of the gage-plate M , the outbent flange of a longitudinally-ranging bar, U , which, with the like bar at the other side of the placer-head, 130 serves as a pair of handles by which, in con-

nection with the power of the springs I at the rear end of the placer-frame, the head may be lifted. The bolt ends n' of the legs N also pass through a pair of transverse parallel 5 plates, L', which are below the head-plate L, and re-enforce it, and the bolt ends n' also pass through a pair of plates, V' V', held one at each side of the placer and between the plates L L', and these plates V' form bearings 10 for the inner ends of fulerum-shafts v of the tripping-levers V of the placer-head, the outer ends of these shafts v having bearings in the ends of horizontal plates V², which are held to the upper parts of the gage-plates M by bolt 15 ends l' , which are formed on the ends of the re-enforcing head-plates L'. The rear bolt ends, l' , also hold to the plates V² the upper ends of bars W, which carry pivotally at their lower ends the roller-detents X, which are held 20 up beneath the outer ends of the trip-rollers S by the rearwardly-extending arms v' of the tripping-levers of the placer. A spring, Y, which is held to the gage-plate M, hangs by its lower end over the upper part of a slot, y, 25 made in said plate, and through or in which slot the opposite ends s s of the trip-roller S turn, and at every half-turn of this roller it will lodge on the detent X, and the spring Y will by springing in over the roller S prevent 30 backward-turning movement of said roller. The pivot or shaft of the detent X is secured both in the bar W and gage-plate M, and thus stays said bar from the plate. It will thus appear that by the use of the two pairs of 35 bolt ends n' and l' at each side of the placer-head I am enabled to make a very substantial and inexpensive construction and combination of parts of the placer.

By reference to Fig. 4 of the drawings it 40 will appear that the trip roller or device S is really a double roller or has a short roller, s, mounted at each end part of it or at each side of the pivot p, on which the device turns to bring the two rollers s s alternately within or 45 across the rail-receiving space O between the gages M N of the placer-head. The tripping-levers V of the placer-head are peculiarly made with two main side bars, one v², on which the horizontally-ranging latch portion v' is pro- 50 vided for the detent X of the roller S, and the other side bar, v³, which is formed with a heel portion, v⁴, which acts against the front part of the placer-leg N as a stop to limit the downward and backward throw of the latch 55 on its pivot or shaft v, which is shouldered at its central part to hold the two latch-bars v² v³ apart, said bars being also stayed to each other by a fixed cross-bar, v⁵, onto which presses the forward end of a spring, Z, which 60 is held at its rear end to the top of the placer-head. This spring normally throws the entire latch downward and rearward and holds the part v' of the latch in proper position to support the detent X and roller S until the 65 latch is operated by upward pressure on a roller, z, which is journaled in any two of series of holes z', which are provided at the

forward ends of the two latch-bars v² v³. By adjusting the roller z higher or lower in the series of holes z' the latch may be tripped 70 later or earlier by contact of the rail with it. One of the latch-levers V is shown in perspective view in Fig. 7. The lever-bar v² is shown in side view in Fig. 5, and the bar v³ is shown in side view in Fig. 3 of the drawings. 75

The operation of the apparatus is as follows: We will suppose that two rails, C, on the car A have been slid toward the outer sides of the car and in position against the shoulders k k of the elastic rod K, and the latch H 80 engaged with the lower notch, g², of the bar G, as shown in Fig. 8 of the drawings, to hold the placer-head up clear of the ties c on the road-bed. These two rails will now be run forward over the car-rollers a⁶ and between 85 the conical or tapering guide-rollers P R and onto the trip-rollers S for a couple of feet. The car A now supporting the rail-placer will be drawn forward on the two rails C C last laid from the placer until at the forward ends 90 of said laid rails, when the brakes D will be applied to stop the car. The lever J' will now be pulled forward, or either one of the arms or levers J² will be pressed down, as may be most convenient, and this will release the 95 latch H and allow the weight of the pair of rails C C on the placer-rollers S S to rock the placer on its U-bolts b' until the legs N rest on the ties, and the latch H will now automatically engage the upper notch, g', of the bar G to 100 lock the placer-head on the ties. The aforesaid lowering of the placer-head will have adjusted the rail-supporting rollers S sufficiently below the car-rollers a⁶ to cause the two rails C C to run forward by gravity, and the rear 105 ends of the rails as they leave the rollers a⁶ will be caught by men, who will swing the back ends of the rails downward on the placer-rollers S as fulerums and as indicated in dotted lines in Fig. 5 of the drawings, their object 110 being to set the back ends of the rails against the forward ends of the rails last laid and on which the car A rests. About at the time the ends of the rails are joined, as aforesaid, or it may be a moment earlier, the rails will strike 115 the rollers z of the levers V and rock them on their pivots v, and thereby withdraw their latch-arms v' from under the detents X, which then will turn down and allow the tripping-roller S to turn as the rails fall by their own 120 weight down in the spaces O O between the two pairs of guides M N and onto the ties, the guides holding the rails to perfect gage. The lever J' or one of the arms J² will now be operated to withdraw the latch H from the 125 notch g' of the bar G, whereupon the springs I I will act instantly to lift the placer-head from the ties, and the latch H will again automatically engage the lower notch, g², of the bar G to hold the placer-head up clear of the 130 ties. Another pair of rails C C will now be adjusted and run forward onto the placer-rollers S a couple of feet, and the car will again be drawn forward until it reaches the

rear ends of the pair of rails just dropped to place, when the brakes D will be again applied, and these rails will be laid to the ties in a manner readily understood from the 5 aforesaid description.

The placer-head guides M N assure the laying or dropping of the rails in true gage, and the car-wheels α^2 co-operate with the placer for like purposes; hence as the rails are laid 10 two at a time or for both rails of the track simultaneously they may be spiked or otherwise secured to the ties or road-bed while the car stands on them, or immediately after the car shall have passed forward over them, and 15 the whole work may be accomplished by a few men and with marked economy of time and labor.

While laying rails on curves of the track the pins F will be shifted either to the right 20 or left hand holes e of the series of said holes in the cross-bars E to swing the rail-placer head either to the left or right hand, as the curves of the track may require. It will be understood that the guide-rollers P R on the 25 placer-head are not essential to the successful operation of the apparatus, and that the rollers s on the pivoted rail-supports S of the placer-head are not necessary, as a plain pivoted shaft or bar may be used, and the trip- 30 lever rollers z may be substituted by plain shafts or bars; but the use of all these rollers is desirable, as they relieve the friction and lessen the labor of working the apparatus. The pivoted detents X may also be dispensed with, 35 as the pivoted rail-supports S may rest directly on the ends r' of the latch-levers; but the detents by having supports on the placer-head relieve the latch-levers of much strain which they would have to bear were the de- 40 tents dispensed with; hence the detents are preferred in practice.

Having thus fully described my invention, what I claim as new, and desire to secure by Letters Patent, is—

45 1. In a track-laying apparatus, the combination, with a movable rail-platform, of a rail-placer consisting of a horizontal forwardly-projecting structure fulcrumed to the platform for vertical movement thereon and pro- 50 vided at its forward part with supports re- ceiving both side rails of a track from said platform, substantially as herein set forth.

55 2. In a track-laying apparatus, the combination, with a movable rail-platform, of a forwardly-projecting rail-placer fulcrumed thereto for vertical movement and provided with front leg-supports adapted to the road-bed, and a detent holding the rail-placer clear of the road-bed as the apparatus moves forward, 60 substantially as herein set forth.

65 3. In a track-laying apparatus, the combination, with a movable rail-platform, of a forwardly-projecting rail-placer fulcrumed thereto for vertical movement and provided with pivoted supports for rails run forward from the platform, and latch-detents adapted to retain the pivoted rail-supports and to be

tripped to allow the rails to drop to the road-bed, substantially as herein set forth.

4. In a track-laying apparatus, the combination, with a movable rail-platform, of a rail-placer fulcrumed thereto for vertical movement and provided at its head with pivoted supports for rails run forward from the platform, latch-detents adapted to retain the pivoted rail-supports, and pendent legs or plates holding the rails in gage as they are dropped from the pivotal supports to the road-bed, substantially as herein set forth.

5. In a track-laying apparatus, the combination, with a movable rail-platform, of a rail-placer fulcrumed thereto and provided at its head with pivoted supports for rails run forward from the platform, and latch-detents adapted to retain said rail-supports, legs on the placer-head adapted to support it from the road-bed, a latch on the rail-platform adapted to hold the placer-head up from the road-bed, and pendent legs or plates forming guides holding the rails in gage as they are 90 dropped from the pivotal supports to the road-bed, substantially as herein set forth.

6. In a track-laying apparatus, the combination, with a movable rail-platform, of a rail-placer held thereto and provided at its head with pivoted supports for rails run forward from the platform, latch-levers fulcrumed on the placer-head and adapted to retain the pivoted supports and the rails thereon, and said latch-levers provided with cross-bars or 100 rollers adapted to be struck by the rails when their rear ends are lowered to automatically trip the pivoted supports and allow the rails to fall to the road-bed, substantially as herein set forth.

105 7. In a track-laying apparatus, the combination, with a movable rail-platform, of a rail-placer held thereto and provided at its head with pivoted supports for rails run forward from the platform, latch-levers fulcrumed on the placer-head and adapted to retain the pivoted supports and the rails thereon, and said latch-levers provided with cross-bars or rollers adapted to be struck by the rails when their rear ends are lowered to automatically trip 115 the pivoted supports and allow the rails to fall to the road-bed, and said rail-platform provided with brake devices adapted for action on the laid rails on which the platform rests to prevent forward movement of the 120 platform while the inclined rear ends of the rails being laid bear on the forward ends of the rails last laid, substantially as herein set forth.

125 8. In a track-laying apparatus, the combination, with a movable rail-platform, of a rail-placer held thereto and provided at its head with pivoted supports for rails run forward from the platform, latch-levers fulcrumed on the placer-head to retain the pivoted supports 130 and the rails thereon, and said latch-levers provided with cross-bars or rollers adapted to be struck by the rails when their rear ends are lowered to automatically trip the pivoted

- supports and allow the rails to fall, and said placer-head also provided with pendent legs or plates holding the rails in gage as they are dropped to the road-bed, substantially as herein set forth.
9. In a track-laying apparatus, the combination, with a rail car or platform, of a rail-placer hung to the platform and provided at its head with pivoted supports for rails run forward from the platform, latch-detents adapted to retain said rail-supports, and pendent legs or plates holding the rails in gage as they are dropped from the pivoted supports to the road-bed, and the rear end of the placer held to the rail-platform, so as to be adjustable laterally to accommodate curves of the road-bed in laying rails thereon, substantially as herein set forth.
10. In a track-laying apparatus, the combination, with a rail car or platform having front rollers, a^6 , of a rail-placer fulcrumed on the platform and provided with tilting rail-supports S, having rollers s, and latch-detents for said supports, substantially as described, whereby when the placer-head is lowered the rails on the rollers a^6 s will run forward by gravity, as and for the purposes set forth.
11. In a track-laying apparatus, the combination, with a rail-car and a rail-placer fulcrumed thereto and provided with pivoted rail-supports and latches therefor, substantially as specified, of a latch-bar, G, on the car and a latch, H, on the placer, substantially as herein set forth.
12. In a track-laying apparatus, the combination, with a rail-car and a rail-placer fulcrumed thereto and having pivoted rail-supports and latches therefor, of springs interposed between the car and placer-frames and latch devices on the car and placer for holding the placer-head clear of the road-bed, substantially as herein set forth.
13. In a track-laying apparatus, the combination, with a rail-car, a rail-placer fulcrumed thereto and provided with pivoted rail-supports and latches therefor, a catch-bar, G, on the car, and a latch, H, on the placer, of a rod, h, connected to the latch, and shaft-and-lever connections to the rod h for operating the latch from the forward end of the car, substantially as herein set forth.
14. In a track-laying apparatus, the combination, with the rail-car A, of an elastic or spring-actuated rod, K, having shoulders k k, forming fulcrums in adjusting the rails, substantially as herein set forth.
15. In a track-laying apparatus, the combination, with a rail car or platform, of a rail-placer held thereto, rail-supports, as S, pivoted to the placer-head, latch-detents for said supports, and springs Y, preventing backward movement of the tripped supports, substantially as herein set forth.
16. In a track-laying apparatus, the rail-placer head provided with pivoted rail-supports S, having rollers s s at opposite ends, substantially as herein set forth.
17. In a track-laying apparatus, the rail-placer head provided with pivoted rail-supports, as S, pivoted detents X therefor, and spring-pressed latch-levers V, having parts v' under the detents, substantially as herein set forth.
18. In a track-laying apparatus, the rail-placer head provided with pivoted rail-supports, as S, pivoted detents X therefor, and spring-pressed latch-levers V, having parts v' under the detents, and also having cross-bar or rollers z, substantially as herein set forth.
19. In a track-laying apparatus, the rail-placer head provided with pivoted rail-supports, as S, rail-guides M N, guide-rollers P R, leading the rails to the supports S and between the guides M N, and latch devices holding the supports S and allowing them to be tripped for dropping the rails to the road-bed between the guides M N, which hold the rails in gage, substantially as herein set forth.
20. In a track-laying apparatus, the rail-placer head provided with pivoted rail-supports, as S, and spring-pressed latch-levers therefor provided with outer bars or rollers, z, arms v' under the supports S, and arms v', forming stops to the levers, substantially as herein set forth.
21. In a track-laying apparatus, the rail-placer head formed with a cross-beam, b², legs N N, held thereto, a head-plate, L, held to the legs, and plates M M, held to the head-plate and parallel with the legs N, and forming therewith guides to hold the rails in gage as they are dropped to the road-bed, substantially as herein set forth.
22. In a track-laying apparatus, the rail-placer formed with beams b b, a cross-beam, b², legs N N, held to the cross-beam, head-plates L L, held to the legs by bolt ends n' thereon, and pendent plates M M, ranging parallel with the legs and said plates L', having bolt ends l', which, with the bolt ends n' of legs N, hold the plates M to the placer-head, substantially as herein set forth.
23. In a track-laying apparatus, the rail-placer having beams b b and a head formed with a cross-beam, b², head-plates L L', legs N N, plates M M, bolt l, and braces l' n², all arranged substantially as herein set forth.
24. In a track-laying apparatus, the tilting rail-placer fulcrumed on a rail car or platform and provided with arms U U on its head, substantially as herein set forth.

FREDRICK HERMAN.
